UNITED STATES PATENT OFFICE.

URBANE J. EWING AND ADA F. EWING, OF WILKINSBURG, PENNSYLVANIA.

MOP AND MOP HOLDER.

Application filed February 15, 1927. Serial No. 168,353.

This invention relates to cleaners, polishers, or mops and mop holders and more especially to that type in which a special form of cleaner, polisher, or mop is adapted to be removably attached to a member which is capable of being secured to a rod or handle so as to enable said cleaner or mop to be used for a variety of purposes.

The objects of the invention are:

- 10 First, to provide a mop and its holder of the character above indicated which is cheap to manufacture and consists of a minimum number of parts and in which the several parts comprising the cooperating elements of the mop and holder can be quickly adjusted and the clamping and unclamping and removal of the mop from the holder can be easily effected with the least number of manual operations.
- 20 Second, to construct a mop and its holder in such a manner so that when the mop has been clamped to the holder said mop can be used in wiping or mopping a plane surface in a horizontal or vertical position only
- 25 the soft texture of the cleaner or mop is capable of coming in contact with the surface of the floor, window, or other surface or body to be cleaned, mopped or polished, thereby preventing the abrasion of the floor
- 30 or scratching of the body surface due to the contact of metal forming the holder with said floor or body surface.

Third, to form a mop and holder which can be used jointly with a polishing or cleaning fluid, said fluid being slowly, properly and uniformly distributed to the active surface of the mop.

Fourth, to provide a holder for the mop which can be applied to and operated from an extended pole or rod for use on the floor, or said rod or pole quickly disconnected from the holder and a handle to be gripped by the fingers readily substituted for said rod or pole without in any way disturbing the adjusted or clamped position of the mop or cleaning surface.

Fifth, to form a mop and mop holder of such shapes, contours and cross sections as will enable said mop and holder to be easily packed for shipment in a minimum of space and at the same time prevent their shapes or any of the cooperating parts from becoming distorted or injured tending to make them inoperative after being unpacked for demonstration or sale.

Sixth, other advantages of the construction and relation of the several parts comprising the cooperating elements of the mop or cleaner and the holder will be apparent from the detailed description to be presently disclosed.

The invention consists of structural characteristics and relative arrangement of elements which will be hereinafter more fully described and particularly pointed out in the appended claims.

In the three sheets of drawings, in which similar reference characters indicate the same parts in the several figures:

Figure 1 is a top perspective view of one form of the combined holder and mop or cleaner.

Figure 2 is an enlarged sectional view taken on line II—II of Figure 1.

Figure 3 is a perspective view on a reduced scale of one form of the mop with the pile or absorbing fabric removed.

Figure 4 is a top plan view of Figure 1 on a reduced scale with the pole or handle and clamping top removed.

Figure 5 is a top plan view of a modified form of the invention.

Figure 6 is an enlarged sectional view taken on line VI—VI of Figure 5.

Figure 7 is a top plan view of the form shown in Figure 5 partly broken with the clamping top removed and a section of the mop detached from the base of the holder.

Figure 8 is an enlarged and fragmentary sectional view of a modified form of clamping top as applied to the base shown in Figure 6.

Figure 9 is a side view of the combined mop and holder shown in Figure 5 with the pole removed and a hand grip substituted.

Figure 10 is a top plan view of a further modified form of the invention.

Figure 11 is a detached and perspective view of the form of handle shown in Figure 10.

Figure 12 is a sectional view taken on line XII—XII of Figure 10.

Figure 13 is a fragment of a top plan view of a corner of the base of the holder shown in Figure 12.

Referring to Figures 1, 2, 3 and 4, 14 represents the receiving base or bottom section, which in in this instance is square in plan view and is provided with a plane bottom 15 having integrally formed at its outer edges a

raised web or flange 16 arranged normal to the plane of the bottom 14 and forming a shallow recess or pocket 17, as clearly shown in Figure 2, and for purposes to be herein-
5 after explained. Rigidly secured to center section of the bottom 14 and projecting up through the pocket or recess 17 are two separated screw threaded pins 18, 18.

19 is a dished upper clamping member comprising a bottom 20 having integrally formed thereon on its outer edges a raised web or flange 21, arranged normal to the plane of the bottom 20 and forming a recess 22 and is of a smaller depth than the web 15 or flange 16 of the base or bottom section 14 and of such shape and size to fit and be easily seated in the shallow recess or pocket 17 of the base section 14 with a slight clearance between the outer sides of the flange 21
20 of the clamping member 19 and the inner sides of the flange or web 16 of the base section, as clearly shown in Figure 2. Said bottom 20 of the clamping member 19 is provided with openings 23, 23, which register with the two screw threaded pins, 18, 18, projecting from the base section 14 for purposes readily understood.

The mop or cleaner consists of two rectangular strips 24 and 25 of cloth or suitable fabric which are superimposed and arranged at right angles to each other and sewed together by stitching 26, as shown in Figure 3, and the underside has stitched or otherwise secured thereto a pile 27 or other absorbent fabric, as shown in Figures 1 and 2. This construction of the mop or cleaner provides two pairs of hinged and oppositely disposed flaps 28, 28, capable of being turned in on each other over the top of center section of the mop free of pile fabric, for purposes to be presently described.

A T-shaped member or socket piece 29 into which is fitted and secured a handle or pole 30 is provided with lateral extensions 31, 31, 45 having openings which register with and are adapted to receive the projecting pins 18, 18, as shown, and 33, 33, are nuts for securing said socket member 29 into the position shown in Figure 1.

50 The manner of assembling the mop or cleaner with the holder is as follows:

The mop or cleaner is placed with its pile or absorbent fabric side on the underside and the hinged flaps 28, 28, are opened out into 55 the position shown in Figure 3. The receiving base or bottom section 14 of the holder is then adjusted so that the flaps 28, 28, can be folded down over the outer flanges 16 and into the recess or pocket 17 of the bottom section 14 and assume the positions as shown in Figure 4. The clamping member 19 is then superimposed with its flanges 21, 21, facing the flaps 28, 28, and its openings 23, 23, registering with and receiving the projecting pins 18, 18, of the bottom section 14

and forced down onto said flaps 28, 28, and into the pocket or recess 17, as clearly shown in Figure 2.

The handle holding member 29 is then adjusted so that its openings 32, 32, register with the pins 18, 18, and the nuts 33, 33, are screwed down, thereby further forcing into the recess or pocket 17 the clamping member 19 and causing its flanges 21 to firmly grip and hold the flaps 28, 28, and immovably secure the mop to its holder under all conditions of service, and due to the two pins 18, 18, engaging the handle holding member 29, said member 29 is incapable of rotation or displacement with respect to its secured position to the clamping member 19 and hence insures at all times and with rough usage the proper relation of the mop with its holder and the operating handle.

In Figures 5, 6, 7, 8 and 9, substantially the same invention is illustrated as that disclosed with respect to Figures 1 to 4 inclusive, except that the form of the mop holder instead of being square or rectangular in shape has been changed to a circular form 85 and is effected by providing the cooperating circular base section 141 and clamping member 191 with the same arrangement and type of screw threaded pins 181, socket piece 291, for securing the handle 30. 90

The circular cooperating mop is made in the same manner as described with reference to Figures 1 to 4, except in order to conform to the circular shapes of the base section 141 and clamping member 191 said 100 mop is preferably provided with hinged flaps 281 having V-shaped sections removed in order to be properly disposed in the pocket of said base section and avoid overlapping the pins 181, as shown in Figure 7. 105

Figure 8 shows a form of the invention in which the clamping member 192 is simply a plate without flanges and the length of the pins 182 is reduced, as shown.

Figure 9 shows a mop and mop holder of the same general type and form as shown in Figures 5 and 7, except instead of long handle 30 being employed, a small curved or hand grip 301 is secured to the pins 181, by the same nuts and makes the mop and its holder capable of being used for washing, polishing or rubbing at a high or low level without necessitating the taking apart of the holder.

In Figures 10, 11, 12 and 13, substantially the same invention as disclosed with respect to Figures 1 to 4 inclusive is shown, except that the bottom 151 of the base receiving section 142 is provided preferably with a plurality of perforations 161 to enable any cleaning, waxing, polishing, or other desirable fluid 171 to pass into the polishing or cleaning fabric 27 of the mop, as will be readily understood.

This type of holder can also be provided 130

with a handle or grip comprising a plate 302 provided with the openings 303 registering with the pins 183 and having the elongated openings 184 at its upturned ends through which is fastened a strap 304, as shown in Figure 12.

From the foregoing disclosure of the construction and arrangement of the improvement and mode of applying the same, it will be seen that all the objects and advantages recited in the statement of invention have been fully and efficiently carried out, and while we have shown and described our preferred forms of mops and mop holders, many changes will readily suggest themselves without in any way departing from the salient features herein disclosed and embodied in the scope of the claims.

What we claim is:

- 20 1. A mop comprising a base section provided about its periphery with a raised web forming a shallow recess or pocket, a plurality of separated pins normal to and rigidly projecting from the base section within the pocket or recess, a dished clamping member adapted to fit with a slight clearance within the recess or pocket and having openings registering with and adapted to receive said separated pins, and means engaging said pins for holding said dished clamping member within said recess or pocket of the base section with the recesses of said clamping member and base section facing each other, and a mop fabric comprising two elongated sections of fabric superimposed at right angles to each other and secured at their overlapping central sections and an absorbent material secured on the outerside of one of the overlapping central sections, thereby forming a structure with a central absorbent section with hinged and flexible flaps extending from said absorbent section, said central absorbent section being disposed on the exterior of the base section and the flexible flaps passing over the top edge of the raised web into the shallow recess of the base section and held between the clamping member and base section. 70
- 25 2. A mop holder comprising a base section having a perforated bottom and provided about its periphery with a raised web forming a shallow recess or pocket, a plurality of separated pins normal to and rigidly projecting from the base section within the pocket or recess, a dished clamping member adapted to fit with a slight clearance within the recess or pocket and having openings registering with and adapted to receive said separated pins, means engaging said pins for holding said dished clamping member within said recess or pocket of the base section with the recesses of said clamping member and base section facing each other, and a mop fabric comprising two elongated sections of fabric superimposed at right angles to each other and secured at their overlapping central sections and an absorbent material secured on the outerside of one of the overlapping central sections, thereby forming a structure with a central absorbent section with hinged and flexible flaps extending from said absorbent section, said central absorbent section being disposed on the exterior of the base section and the flexible flaps passing over the top edge of the raised web into the shallow recess of the base section and held between the clamping member and base section. 75
- 30 3. A mop comprising two elongated sections of fabric having V-shaped incisions in their ends and superimposed at right angles to each other and secured at their overlapping central sections and an absorbent material secured on the outerside of one of the overlapping central sections, thereby forming a structure with a central absorbent section with hinged and flexible flaps extending from said absorbent section. 80
- 35 4. In testimony whereof we hereunto affix 90 our signatures.
